EDWARD E. ROSE, OF EDGEWOOD PARK, PENNSYLVANIA, ASSIGNOR TO WESTINGHOUSE ELECTRIC & MANUFACTURING COMPANY, A CORPORATION OF PENNSYLVANIA.

TROLLEY-FROG APPROACH.

1,406,286.

Specification of Letters Patent. Patented Feb. 14, 1922.

Application filed March 31, 1920. Serial No. 370,138.

To all whom it may concern:

Be it known that I, EDWARD E. ROSE, a citizen of the United States, and a resident of Edgewood Park, in the county of Allegheny and State of Pennsylvania, have invented a new and useful Improvement in Trolley-Frog Approaches, of which the following is a specification.

My invention relates to trolley-conductor devices and particularly to approach members for frogs, crossings and similar structures.

One object of my invention is to provide a device of the above indicated character that shall permit of the convenient assembly thereof from a position at the side of a trolley conductor.

Another object of my invention is to provide a trolley-frog approach member and a wedge therefor that shall be so formed and related as to automatically bend a trolley conductor during the operation of attaching the approach member to the frog.

Another object of my invention is to provide a trolley-conductor device that shall comprise a relatively-small number of parts, which may be readily assembled on a conductor by the use of only a relatively simple tool, such as a hammer.

In a frog, crossing, section-break, splice and similar device for attachment to a trolley conductor, a renewable approach or arc-taking member therefor is desirable to prolong the life of the device and prevent interruptions to the service. This renewable member should be permitted of mounting and dismounting in as short a space of time, and with as great facility, as it is possible to attain, consequently, nuts, bolts and other

loose parts that are difficult to manipulate and that may become rusted should be avoided. Further, by reason of the position of the conductor with respect to the attaching parts and with respect to overhead structures, it is desirable that the operator be permitted as much freedom of movement as possible.

Heretofore, it has been usual to employ wedges and clamps which have, to the best of my knowledge, nearly all been operable at positions above the conductor. This may be convenient in a great many installations but frequently the manipulation of a wrench or hammer is interfered with by the lack of headroom.

In practicing my invention, I provide means whereby a wedge for holding an approach member to a frog may be easily driven home from a position beside the trolley conductor. Also, the frog and the approach member are so shaped as to permit the automatic bending of the conductor during the operation of driving the wedge.

Figure 1 of the accompanying drawings is a side elevational view of one end of a trolley-frog and approach member embodying my invention, during the operation of assembling the device; Fig. 2 is a view similar to Fig. 1, showing the parts assembled, and Fig. 3 is a view taken along the line III—III of Fig. 2.

In general, my device comprises a frog or similar member 1, only a portion of which is shown, of substantially channel shape, for the reception therein of a trolley conductor 2, and an approach member 3 that functions to hold the conductor against the bottom of the channel and to take the arcs occasioned by passing trolleys.

The inner bottom surface of the member 1 is formed for a short distance from the end thereof to lie in the direction of the conductor 2 and, at a portion 4, is inclined upwardly from the horizontal portion. This removes the curvature in the bent-conductor 80 from adjacent the extreme end of the frog 1 and permits the approach member 3 to be effectively fitted in position.

Lugs 5, at the ends of the upper edges of the frog 1 have oppositely-disposed transversely-extending rectangular openings 6 which provide relatively-large interior areas to effect good engaging surface co-operation with a wedge 7.

The approach member 3 has depending sides 8 for gripping engagement with the conductor 2 and a projection or tongue 9 for positioning in the channel of the frog 1 above the conductor 2. The under surface 10 of the tongue 9 is formed partially horizontal and partially inclined in order that it may snugly fit the conductor throughout its longitudinal portion in the channel and for a portion of its inclined position therein. The upper surface of the tongue 9 is inclined upwardly toward the frog body so that, when the wedge 7 is in operative position, the tongue 9 is substantially interlocked with the frog 1 to prevent its withdrawal therefrom along the conductor 2. 110

In assembling the device, the parts are first placed together as shown in Fig. 1. In this relation, the normally-straight conductor 2 does not conform to the irregular inner 5 bottom surface of the frog and the tongue 9 is, thereby, so positioned as to partially obstruct the openings 6. The wedge 7 is then placed in the openings 6 and driven 10 home with sufficient force to bend the conductor 2 into conformity with the bottom of the channel. The engaging surfaces of 15 the wedge 7, the lugs 5 and of the tongue 9 being of relatively great area and the parts being held together under relatively great binding forces, the conductor 2 and the approach member 3 are effectively secured in operative positions.

The wedge 7, being permitted of insertion and withdrawal in a direction transverse to 20 the conductor 2, greatly facilitates the assembly and disassembly of the device.

While I have shown and described a particular form of my invention, changes may be effected therein without departing from 25 the spirit and scope thereof, as set forth in the appended claims.

I claim as my invention:

1. A trolley-conductor device comprising a body member of channel-shape for the 30 reception of a conductor, said body member having wedge-receiving means extending transversely with respect to said channel, an approach member having a tongue projecting into said channel, and a wedge co-operating 35 with said wedge-receiving means and said tongue to hold the approach member in position.

2. A trolley-conductor device comprising a body member, an approach member there- 40 for, and a wedge member co-operating with both of said members to bend a trolley conductor into position on the body member and to hold said approach member in opera- 45 tive position.

45 3. A trolley-conductor device comprising a body member of channel-shape for the reception of a conductor, said body member having wedge-receiving means, an approach member having a tongue projecting into 50 said channel, and a wedge co-operating with said wedge-receiving means and said tongue to bend a trolley conductor into conformity with the channel and to hold said approach member in operative position.

55 4. A trolley-conductor device comprising a body member of channel-shape for the reception of a conductor, said body member having wedge-receiving means extending transversely with respect to said channel, 60 an approach member having a tongue projecting into said channel and a wedge co-operating with said wedge-receiving means and said tongue to bend a trolley conductor into conformity with the channel and to hold 65 said approach member in operative position.

5. A trolley-conductor device comprising a body member of channel-shape having op- 70 positely-registering apertured lugs adjacent to one end thereof, an approach member hav- 75 ing a tongue projecting into the channel to a position between the lugs, and a transverse wedge extending through the lugs and en- 80 gaging the tongue to hold the approach member in position.

6. A trolley-conductor device comprising 75 a body member of channel-shape having an irregular bottom surface and oppositely- 80 registering apertured end lugs at the upper edges of the channel, an approach member having a tongue projecting into the channel 85 to a position between the lugs, and a trans- 90 verse wedge extending through the lugs and en- 95 gaging the tongue to bend a trolley conductor into conformity with the said irregular bottom surface and to hold the approach member in position.

7. A trolley-conductor device comprising a body member of channel-shape for the re- 95 ception of a conductor, said member having oppositely - registering apertures extending 100 transversely with respect to the channel, an approach member having a portion extend- 105 ing into the channel at one side of said ap- 110 pertures and a transverse wedge member co- 115 operating with the body member in said ap- 120 pertures and with said approach member to hold the latter in position and to clamp a 125 conductor against the body member.

8. A trolley-conductor device comprising 100 a body member of channel-shape for the re- 105 ception of a conductor, said member having a partially horizontal and a partially in- 110 clined bottom surface, transversely-extending 115 wedge-receiving means on said member, an approach member having a portion ex- 120 tending into the channel to a position adja- 125 cent said wedge-receiving means, and a 130 transverse wedge member co-operating with the wedge-receiving means and the approach member to bend a trolley conductor into 135 conformity with said bottom surface and to hold all of said members together.

9. A trolley-conductor device comprising a body member of channel-shape for the re- 115 ception of a conductor at the bottom of the 120 channel, said member having upwardly and 125 outwardly-projecting transverely - recessed lugs and a partially horizontal and par- 130 tially-inclined bottom inner surface, an ap- 135 proach member having a tongue extending into the channel above the conductor and below the lugs and having its under sur- 140 face partially horizontal and partially in- 145 clined, and a transverse wedge member co- 150 operating with said lugs and the upper side 155 of said tongue to hold the parts together and to hold the conductor in securely-clamped 160 position.

10. A trolley-conductor device comprising a body member having a wedge-receiving 165

portion, a renewable approach member therefor and a wedge member engaging both of said members to hold the approach member in position, said wedge and said approach member having co-operating surfaces inclined in two directions by which the approach member is clamped against a conductor and prevented from longitudinal movement therealong.

10 11. A trolley-conductor device comprising a body member having a wedge-receiving portion, a renewable approach member therefor and a wedge member engaging both of said members to hold the approach member in position, said wedge and said approach member having co-operating portions constructed and related to clamp the approach member in position and to pre-

vent the longitudinal displacement thereof along the conductor. 20

12. A trolley-conductor device comprising a body member, an approach member therefor and wedging means for clamping the approach member in position and preventing its withdrawal from position. 25

13. A trolley-conductor device comprising a body member, an approach member therefor and wedging means for clamping the approach member in position and shaped to co-operate with the body member to prevent 30 withdrawal of the approach member.

In testimony whereof, I have hereunto subscribed my name this 12th day of March, 1920.

EDWARD E. ROSE.
